UNITED STATES PATENT OFFICE.

WILLIAM E. FISHER, OF SUSQUEHANNA, PENNSYLVANIA.

DRAIN-COCK.

1,161,648.

Specification of Letters Patent.

Patented Nov. 23, 1915.

Application filed May 19, 1915. Serial No. 29,205.

To all whom it may concern:

Be it known that I, WILLIAM E. FISHER, a citizen of the United States, residing at Susquehanna, in the county of Susquehanna and State of Pennsylvania, have invented certain new and useful Improvements in Drain-Cocks, of which the following is a specification, reference being had to the accompanying drawings.

0 This invention relates to certain improvements in drain cocks and has relation more particularly to a device of this general character especially designed and adapted for use in connection with the cylinders of steam 15 operated engines; and it is an object of my invention to provide a novel and improved device of this general character whereby a cylinder is thoroughly drained in substantially an automatic manner.

20 The invention consists in the details of construction and in the combination and arrangement of the several parts of my improved drain cock whereby certain important advantages are attained and the device 25 is rendered simpler, less expensive and otherwise more convenient and advantageous for use all as will be hereinafter more fully set forth.

The novel features of the invention will 30 be carefully defined in the appended claims.

In order that my invention may be the better understood, I will now proceed to describe the same with reference to the accompanying drawings, wherein—

35 Figure 1 is a longitudinal sectional view taken through a drain cock constructed in accordance with an embodiment of my invention; and Fig. 2 is a transverse sectional view taken through the device as disclosed 40 in Fig. 1.

As disclosed in the accompanying drawings, 1 denotes the casing of my improved valve having one extremity 2 reduced and exteriorly threaded so that the same may 45 be readily applied to a cylinder C and the opposite end of said casing 1 is open and adapted to be closed by the removable cap 3 provided with the tubular extension 4. The extension 4 is provided with the alined 50 longitudinal slots 5 through which the operating member 6 is adapted to extend, said member 6 being herein disclosed as a cam element intended for a purpose which will hereinafter be self-evident. It is preferred 55 that the member 6 be manually operated,

although I do not wish to be understood as limiting myself to this manner.

The inner end of the chamber of the casing 1 is provided with the valve seat 7 with which coacts the valve 8, said valve being 60 normally maintained in contact with its seat under the influence of the expansible member 9, herein disclosed as a conventional coil spring, interposed between the annular shoulder 10 of the valve 8 and the cap 3. 65 The spring 9 is preferably set for forty pounds above boiler pressure, although it will be readily appreciated that the tension of the spring may be controlled by the cap 3. The valve 8 is of a transverse diameter 70 less than the corresponding diameter of the compartment of the casing 1 and the casing 1 is provided with the inwardly disposed radially spaced lugs 11 for guiding the valve, as is believed to be clearly shown in 75 the accompanying drawings. The valve 8 is provided with an axial opening 12 in communication with the tubular extension 14 carried by the valve, and the inner end of the opening 12 is provided with the valve 80 seat 15 with which coacts the valve 16 mounted upon the stem 17 extending beyond the outer end of the extension and passing within the extension 4 of the cap 3, said stem being adapted for engagement by 85 the operating member 6 whereby the same may be raised and positively held in open position.

The outer extremity of the extension 14 is provided with the inwardly disposed lugs 90 18 which serve as guides for the stem 17 and interposed between said lugs 18 and the valve 16 is the expansible member 19, herein disclosed as a conventional coil spring, and preferably set for a pressure of forty pounds. 95 When the steam is admitted within the cylinder C, a pressure of more than forty pounds is required to close the valve 16 which is normally held off of its seat by the expansible member 19. As steam is admitted within the cylinder when cold, the steam condenses and such condensation will be forced out of the cylinder and through the opening 12 and through the openings 23 in the tubular extension 14 arranged intermediate the length of said extension. When the pressure within the cylinder becomes twenty pounds more than boiler pressure, the tension of the expansible member 9 is overcome and the valve 8 opens and thus 100 105 110

assures the discharge of the water within the cylinder before sufficient pressure has been accumulated to blow out the cylinder head or to crack the cylinder.

5 21 denotes a discharge elbow in communication with the chamber of the casing 1 and it is to be noted that this elbow is capable of axial adjustment so that the water of condensation may drain under the 10 engine or in any direction desired.

22 denotes a cap nut removably engaged with the valve 8 and serves to limit the movement of the valve 16 away from its seat. It is also to be observed that with 15 the valve 16 in contact with the nut 22 the entry of cold air within the cylinder is substantially prevented. This is an essential feature of my invention, as otherwise the cold air would be drawn into the cylinder 20 when the engine is drifted, would carbonize the oil and would destroy its lubricating qualities, resulting in broken cylinder packing and cut cylinders.

From the foregoing description, it is 25 thought to be obvious that a drain cock constructed in accordance with my invention is of an extremely simple and comparatively inexpensive nature and is particularly well adapted for use by reason of the convenience and facility with which it may be assembled, and it will also be obvious that my 30 invention is susceptible of some change and modification without material departure from the scope of the appended claims and 35 for this reason I do not wish to be understood as limiting myself to the precise arrangement and formation of the several parts herein shown in carrying out my invention in practice.

40 I claim:

1. A drain cock comprising a tubular casing having an interior valve seat, a movable valve within the casing coacting with the valve seat, said valve being tubular and the 45 bore thereof being provided with a valve seat intermediate the length thereof, means for normally maintaining the valve closed,

said valve being provided with openings in communication with the bore thereof and with the interior of the casing, a movable 50 valve coacting with the valve seat within the bore of the first named valve, said last named valve extending exteriorly of the first named valve, automatic means for maintaining the second named valve open, 55 mechanical means coacting with the stem of the second named valve for positively retaining said second named valve for open adjustment, and a cap nut engaged with the first named valve above the seat therein and 60 with which the second valve is adapted to contact.

2. A drain cock comprising a tubular casing having an interior valve seat, a movable valve within the casing coacting with the valve seat, said valve being tubular and the bore thereof being provided with a valve seat intermediate the length thereof, means for normally maintaining the valve closed, 65 said valve being provided with openings in communication with the bore thereof and with the interior of the casing, a movable valve coacting with the valve seat within the bore of the first named valve, said last named valve extending exteriorly of the 70 first named valve, automatic means for maintaining the second named valve open, mechanical means coacting with the stem of the second named valve for positively retaining said second named valve for open 75 adjustment, a cap nut engaged with the first named valve above the seat therein and with which the second valve is adapted to contact, and a discharge elbow in communication 80 with the interior of the casing at a point intermediate the length thereof, said elbow being capable of axial adjustment.

In testimony whereof I hereunto affix my signature in the presence of two witnesses.

WILLIAM E. FISHER.
